RECORDING SWITCH MECHANISM

Filed Aug. 27, 1925

UNITED STATES PATENT OFFICE

THOMAS R. HARRISON, OF PHILADELPHIA, PENNSYLVANIA, ASSIGNOR TO THE BROWN INSTRUMENT COMPANY, OF PHILADELPHIA, PENNSYLVANIA, A CORPORATION OF PENNSYLVANIA

RECORDING SWITCH MECHANISM

Application filed August 27, 1925. Serial No. 52,745.

My present invention consists in a novel switch mechanism devised with the general object in view of providing a simple, reliable, and effective mechanism for connecting an electric meter first into one and then into another of a plurality of electric circuits in regular succession. The meter with which the switch may advantageously be used may be a simple indicating instrument, but ordinarily will be a recording or recording and control meter. The invention is especially useful in pyrometric work with the electric circuits into which the meter is connected energized by thermo-couples and with the current creating voltages consequently minute. The invention is characterized by the simplicity in construction and effectiveness in operation of the switch mechanism, and particularly by the provisions made for maintaining the switch contact members in a bath of oil or like liquid which prevents surface oxidation or corrosion of, or dirt accumulations on the switch contact members, and thereby tends to a minimum contact resistance. This is especially advantageous with the low voltages existing in pyrometer circuits, and with the tendency to oxidation, corrosion and dirt accumulations when the instrument is located in an atmosphere containing furnace dust or fumes. The various features of novelty which characterize my invention are pointed out with particularity in the claims annexed to and forming a part of the specification. For a better understanding of the invention, however, its advantages and specific objects attained with its use, reference should be had to the accompanying drawings and descriptive matter in which I have illustrated and described preferred embodiments of my invention.

Of the drawings:

Fig. 1 is an elevation partly in section of a portion of a meter equipped with my improved switch mechanism;

Fig. 2 is an end elevation of the apparatus shown in Fig. 1 with the lower portion of the apparatus in section on the line 2—2 of Fig. 1;

Fig. 3 is a diagrammatic representation of

the meter and circuits with which the switch mechanism may be used; and

Fig. 4 is a diagram illustrating a modification.

In the drawings, and referring first to the preferred construction shown in Figs. 1-3, K' is a vertically disposed cylinder integrally connected at its upper end to a switch support or body K formed of a suitable insulating material such as bakelite which is not injuriously affected by contact with the oil or other liquid in which the switch contacts are immersed. Mounted on the lower end of the part K' and extending circumferentially along the periphery of the latter are upper and lower contacts C and D each of which might be a complete circle, but as shown, is an arc of a trifle less than 360°. Between the contacts C and D are an upper intermediate set of contacts G', G², G³, and G⁴, corresponding in number to the circuits into which the switch mechanism is to connect the meter and a lower intermediate set of contacts H', H², H³, and H⁴. The contacts G', G², G³ and G⁴ are arranged in a circular series, each contact being in the form of an arc of slightly less than 90°, and the adjacent sections being similarly spaced apart. The contacts H', H², H³, and H⁴ are similar in form and relative disposition to the contacts G', G², G³, and G⁴. The various contacts C, D, H', etc., advantageously may each be in the form of a suitably curved length of platinum wire secured in place on the barrel K' by having its ends extended through the latter. One end of each contact thus extending through the barrel may be connected to a lead passing through the body K for connecting the contact, as shown in Fig. 3, into the appropriate circuit external to the switch mechanism, but I have not thought it necessary to show these leads in Figs. 1 and 2.

Axially disposed in the barrel K' and journaled in a central tubular boss K² depending from the under side of the body K is a shaft I' which carries at its upper end a bevel gear in mesh with a bevel gear B¹² carried by an actuating shaft B¹¹. At its lower end the shaft I' carries a cross head or brush support I on which is mounted a pair of flexible me-

talic brushes or spring contact members E and F. As the shaft I' is rotated, the brush E successively connects the contacts G', G², G³, and G⁴ with the contact C, and the brush F successively connects the contacts H', H², H³, and H⁴ with the contact D.

The switch supporting body K is formed with a depending flange portion K² surrounding the barrel portion K' and internally threaded to receive the externally threaded 10 upper end of a cup-shaped container L which is advantageously made of glass, and is filled with oil or other suitable liquid to a level above the contact C and brush E, so that the various contacts and brushes are protected by 15 the liquid against surface oxidation, corrosion, or surface dirt accumulations tending to increase the contact resistance.

The support K may advantageously be secured to the frame-work of the meter with 20 which the switch mechanism is used. For example, the plates B¹⁰ between which the support K is shown as secured by screws K⁴, may well be the side members of the motor mechanism provided to depress the meter pointer 25 and advance the chart or record strip in such an instrument, as is shown, for example, in the application of Richard P. Brown, Serial No. 756,475, filed December 1, 1924. In such case, the shaft B¹¹ may be driven through suitable gearing from the pointer depressing and chart feeding motor. Advantageously, the switch supporting member K is provided at 30 the front end of the instrument with a dial swept by a pointer M carried by the end of the shaft B¹¹ and indicating the position of 35 the brushes E and F relative to the various switch contacts G', G², etc., H', H², etc.

Fig. 3 diagrammatically illustrates the use 40 of the switch mechanism shown in Figs. 1 and 2, for successively connecting thermo-couples A', A², A³, and A⁴, to the terminals of the winding of a galvanometer or other meter B provided with a pointer B³ for impressing 45 on a record chart, records O', O², O³, and O⁴, corresponding to the temperatures to which the thermo-couples A', A², A³, and A⁴ are respectively subjected. In Fig. 3 the winding of the meter B has one terminal B' connected 50 to the contact E, and its other terminal connected to the contact F. One terminal, for example the positive terminal, of the thermo-couple A' is connected to the switch contact G', while the positive terminals of the thermo-couples A², A³, and A⁴ are connected, 55 respectively, to the switch contacts G², G³, and G⁴. The other terminals of the thermo-couples A', A², A³, and A⁴ are connected to the switch contacts H', H², H³, and H⁴, respectively. 60 As the brushes E and F are diametrically opposed, the contacts G' and H' are also diametrically opposed, and the same is true of the contacts G² and H², G³ and H³, and G⁴ and H⁴.

With the described arrangement when the

pointer M is opposite the numeral 1 on the dial, brush E engages the contact G' and the brush F engages the contact H'. This connects the thermo-couple A' to the meter B, and the pointer B³ of the latter then indicates the value of the temperature to which the thermo-couple A' is exposed and is in position to make an impression in the record chart line O' constituting the record of the temperature measured by the thermo-couple A'. As the shaft B¹¹ is rotated to bring the pointer M opposite the dial numeral 2, the brushes E and F are brought into engagement with the contacts G² and H², respectively, connecting the thermo-couple A² to the meter B'. Similarly 70 as the pointer M passes through the dial positions 3 and 4 the thermo-couples A³ and A⁴ are successively connected to the meter B. The brushes E and F are shown as flat springs, and preferably the extent of their contact engaging surface is sufficient to bridge the gaps between the contact sections H', H², and H³, etc., G', G², and G³, etc. as well as the gaps between the ends of the contacts C and D so that the current through the meter is not 80 interrupted as the different thermo-couples are successively connected into the meter. This reduces the movement of the meter pointer and eliminates the shocks on the movable element of the meter which would result if the 85 meter circuit were opened in changing from one thermo-couple to the other so that the meter pointer would then return to zero.

Those skilled in the art will understand that any one of numerous liquids may be 90 used to form the protective bath for the switch contacts and brushes. Ordinarily I prefer to use some relatively thin or non viscous hydrocarbon oil which evaporates at 95 a relatively slow rate and is relatively uninflammable. A practical advantage of the construction illustrated is that with the container L somewhat less than half filled with liquid as indicated, and with the elongated depending hub K² at the margin of the opening through the member K for the shaft I, the liquid will not spill out of the container when the instrument is tipped over as it may be in mounting it on, or dismounting it from the instrument panel by which it 100 is normally carried. The protective effect of the contact member immersing bath is especially valuable in pyrometry work because pyrometer meters are frequently employed in an atmosphere containing corroding furnace fumes. The protective effect of the contact member immersing bath is especially valuable for use in pyrometers including thermo-couples, because of the small 105 thermo-couple E. M. F. usually less than one tenth of a volt, makes it highly desirable to keep the contact surfaces free from dirt and oxidized films which tend to vary and unduly increase the switch contact resistance. Trouble from such films is especially apt to 110

occur because pyrometer switches are frequently exposed to furnace fumes tending to corrode the switch contact surfaces if the latter are not protected as herein provided for. I am aware, of course, of the common use of so called oil switches, but in such switches the switch members are primarily immersed in oil to minimize arcing. In instrument switches, the voltages employed are 10 altogether too small to create arcing troubles, and the immersing liquid is employed to prevent variations in contact resistance of a magnitude so small as to be inconsequential in the case of ordinary switches immersed in 15 oil to minimize arcing.

It will be apparent, of course, that one set of intermediate contacts, for instance the contacts G' , G^2 , G^3 , and G^4 , the adjacent continuous contact C , and the brush E , shown 20 in Figs. 1, 2, and 3, may be dispensed with without change in the general mode of the operation of the apparatus provided the terminals of the thermo-couples A' , A^2 , A^3 , and A^4 shown in Fig. 3 as connected to the switch 25 contacts G' , G^2 , G^3 , and G^4 , respectively, are directly connected to the corresponding meter terminal B' as shown in Fig. 4. While the arrangement of Fig. 4 is somewhat simpler, I ordinarily prefer in practice to 30 employ the construction shown in Figs. 1 to 3.

While in accordance with the provisions of the statutes, I have illustrated and described the best form of embodiment of my invention now known to me, it will be apparent to 35 those skilled in the art that changes may be made in the form of the apparatus disclosed without departing from the spirit of my invention as set forth in the appended claims 40 and that in some cases certain features of my invention may be used to advantage without a corresponding use of other features.

Having now described my invention, what I claim as new and desire to secure by Letters 45 Patent, is:

1. In a meter switch mechanism, a supporting structure comprising a depending barrel of insulating material, a vertical shaft axially disposed in said barrel, mechanism 50 carried by said supporting structure including a gear connection to the upper end of said shaft for rotating the latter, a contact carrier secured to the lower end of said shaft, circular sets of arc shaped meter circuit contacts 55 carried by said barrel and exposed at the periphery thereof, and contacts supported by said carrier and engaging and disengaging the different contacts carried by said barrel as said shaft is rotated to thereby successively 60 energize different meter circuits, a cup-shaped oil container into which said barrel extends, and means detachably securing said container to said support.

2. In a meter switch mechanism, a supporting structure comprising a depending barrel

of insulating material and a threaded portion surrounding the upper end of the barrel, a vertical shaft axially disposed in said barrel, mechanism carried on said support including a gear connection to the upper end of said shaft for rotating the latter, a contact carrier secured to the lower end of said shaft, circular sets of arc shaped meter circuit contacts carried by said barrel and exposed at the periphery thereof, and contacts supported by 70 said carrier and engaging and disengaging the first mentioned contacts as said shaft is rotated to successively energize different meter circuits, a cup-shaped glass oil container into which said barrel extends, said container having a threaded portion at its upper 75 end in threaded engagement with the threaded portion of said structure.

3. In a meter switch mechanism, a supporting structure comprising a depending barrel 80 of insulating material and an internally threaded depending flange surrounding the upper end of the barrel, a vertical shaft axially disposed in said barrel, mechanism carried on said support including a gear connection to the upper end of said shaft for rotating the latter, a contact carrier secured to the lower end of said shaft, circular sets of arc shaped meter circuit contacts carried by said barrel and exposed at the periphery thereof, 85 and contacts supported by said carrier and engaging and disengaging the first mentioned contacts as said shaft is rotated to successively energize different meter circuits, a cup-shaped glass oil container into which said barrel extends, said container having its upper end externally threaded and in threaded engagement with said flange.

4. In a meter switch mechanism, a supporting structure comprising a depending barrel 90 of insulating material, a vertical shaft axially disposed in said barrel, mechanism carried by said supporting structure including a gear connection to the upper end of said shaft for revolving the latter, a contact carrier secured to the lower end of said shaft, contacts carried by said carrier, precious metal wires carried by said barrel and forming side by side circular sets of arc shaped meter circuit contacts at the outer surface of said barrel 95 providing tracks along which the first mentioned contacts slide as said shaft is revolved, a cup-shaped oil container into which said barrel extends, and means detachably securing said container to said support.

Signed at Philadelphia, in the county of Philadelphia and State of Pennsylvania, this 24th day of August, A. D. 1925.

THOMAS R. HARRISON.
